ABSTRACT OF THE DISCLOSURE

A convenient personal implement in a suitably closed case adapted to be carried in a pocket of a user and having a removable cap which exposes the cutting edges which are blunt to avoid a needle-like instrument which is dangerous in the use of personal trimming in or about the nose wherein the scissors are actuated by a push button mechanism to improve the convenience and to avoid the awkwardness of conventional scissor operation.

RELATED APPLICATIONS

The present application corresponds to an application filed Oct. 27, 1967, in Japan, bearing Ser. No. 42,68926.

DESCRIPTION OF INVENTION

The present invention relates to an improved personal pair of scissors, a pair of scissors especially adapted for use in trimming the hairs of the nostril. Scissors to which the present invention relate have several disadvantages arising from the fact that they are too small to be skillfully manipulated by the hands of an adult, too small to carry in the pocket or elsewhere on the person. Moreover, if they are made sufficiently large to be adeptly used by a person of adult proportions, then they become too large to be inserted in the nose and to be used at other sensitive places or areas of the body. The present invention avoids the disadvantages and shortcomings of scissors known in the prior art by providing an apparatus which includes a small pair of scissors preferably enclosed within a tubular container or cylinder and which, on uncapping, provides a pair of scissors which are actuated by a push button control which provides the trimming or cutting desired of the present invention. Moreover, the scissors remain within the case while serving their primary function and are readily accessible on capping or uncapping the case. The scissors are provided with a handle which fits within the hand of the user and includes a push button actuator for convenience in use and operation.

The invention will be more readily understood upon reference to the following specification considered in conjunction with the accompanying drawings in which:

FIG. 1 is a front elevational view of the scissors enclosed within the case of the present invention;

FIG. 2 is a longitudinal sectional view of the structure shown in FIG. 1 showing details of internal construction;

FIG. 3 is an enlarged sectional view taken along the line A—A of FIG. 2 showing the pivot of the scissor blades;

FIG. 4 is a sectional view taken along the line B—B of FIG. 2 showing construction of the push button operating mechanism of the present invention; and,

FIG. 5 is a sectional view taken along the line C—C of FIG. 2 showing utilization of the after portions or handle of the device in which a storage compartment is provided.

Referring to the drawings, an elongate and substantially cylindrical holder 1 encloses the components of the present invention as shown in FIG. 1. A tubular handle portion 14 is provided and is connected to an expanded central portion which is divided at a cap 13 which tapers to a point as shown in the drawings. The cap 13 is threadably

2

disengaged from the body portions proper as shown in the sectional view of FIG. 2 to disclose the scissors of the present invention. The scissors of the present invention incorporate a fixed snipping strip 2 which has a forwardly located cutting edge near the point thereof. A movable snipping strip 4 has a forward cutting edge 6 which cooperates with the cutting edge 3 on the opposing snipping strip 2 to provide the appropriate snipping action. It will be noted that the forwardmost ends of the scissors are bluntly shaped, not pointed, to avoid injuring the delicate tissues of the nose and other parts of the body for which the present invention is intended.

The snipping strips 2 and 4 are rotatably pivoted on an axis 5. The axis is passed through appropriate openings in the respective snipping strips to join or pin the two strips together. The strips are flush one against the other at the cutting edges to provide the appropriate scissor action as will be appreciated. Both the cutting edges 3 and 6 protrude or extend from the forward end of the housing 20 1 when the cap 13 is removed from the threaded lip.

Referring to FIG. 2, it will be noted that the axis 5 is enlarged at opposite ends to clamp the two snipping strips one to the other.

The snipping strip 2 is fixed in position in the housing 25 for a holder 1. The snipping strip 4 is movable about the pivot 5. The rearward portions of the snipping strip 4 are indicated by the numeral 7 and are L-shaped to project outwardly through a side opening or port 8 with a push button 9 placed on the rearward portion 7. A spring 10 is 30 connected to both snipping strips 2 and 4. The sectional view of FIG. 4 shows connection of the spring 10 to the snipping strips 2 and 4 near the L-shaped rearward portion 7 as noted above. The spring 10 is fixed at both ends on mounting pins 11 and 12 as shown in FIG. 2. The mounting of the spring causes the rearward portion 7 to rotate 35 outwardly as viewed in FIG. 2.

The cap 13 is secured to the cylindrical holder 1 of the present invention by a suitable means, such as the threaded lip shown in the drawings. A substantially cylindrical and 40 hollow handle 14 is detachably inserted into a tapered port or opening 15 at the rear of the holder 1. The hollow handle 14 provides a chamber which will store an ear cleaning device or the like. As shown in FIG. 1, the cap 13 has a suitable eyelet for receiving ornamental decorations of desired color, length or shape, or may receive a chain or swivel to attach the present invention on or about the user.

In conventional scissors for trimming vibrissa, two fingers are inserted through the two ring-like openings of the two handles of the scissors to achieve the cutting action by opening or shutting repetitively in the same way that ordinary scissors are used. Scissors of this kind have not been able to avoid this inherent defect in cutting operation which results from the manner of operation with handles which are all too often too short to provide the proper cutting action. To avoid the above described defect, the present invention utilizes the push button 9 to actuate the scissors. The push button 9 projects from the holder 1, is first pushed to cause the cutting edge 6 to close with respect to the cutting edge 3 and is then released. On release, the spring 10 returns the cutting edge 6 to its original open posture with respect to the cutting edge 3. The simple movement of the fingers of the user in actuating the push button 9 with respect to the holder 1 is readily achieved by the user. Clearly, the handle 14 enables the user to grip the holder 1 with unusual ease so that the device is readily used for the purpose intended. The relatively short cutting edges 3 and 6 having the rounded or blunted forward portions to thereby protect the user from harm when the cutting edges 3 and 6 are placed within the nostril. Further, the rounded tips of the cutting edges 3

and 6 do not enter too deeply into the nostril of the user because the holder 1 bulges substantially at the threaded lip to deny entry of the holder into the nostril.

The ear cleaning device 16 stored in the handle 14 of the holder 1 is used in a quite conventional way.

In appearance, the holder 1, cap 13 and 14 may be formed of metal or suitable synthetic resins. Attractive appearance of the device is readily achieved.

The preferred embodiment of the present invention is sufficiently handy to be safely carried on the person of the user with the scissors housed in the holder 14 at the cap 13.

Several variations and changes may be utilized within the scope of the present invention. The connecting means of the handle 14 and the holder 1 are not limited to the means described hereinbefore. Also, it may be possible to store another suitable device in the handle 14 instead of the ear cleaning device which is illustrated. Also, the handle 14 may be formed so as to function as a fountain pen or a ball point pen.

Other modifications of the preferred embodiment may suggest themselves. However, the present invention is described by the claims appended hereto.

I claim:

1. A pair of scissors adapted for trimming the hairs of the nostril which comprise:
  - (a) a case;
  - (b) a pair of scissors comprising a pair of snipping strips mounted in said case;
  - (c) cutting edges of said scissors projecting from a portion of said case; and,
  - (d) means for moving one of said snipping strips with respect to the other which engages the rearward por-

tions of one of said snipping strips and provides a means for actuation thereof extending from within said case to permit hand operation.

2. The invention of claim 1 wherein one of said snipping strips is fixed with respect to said case and the other is rotatably pivoted on said one snipping strip, and including spring means operatively connected between said strips to thereby provide relative movement.

3. The invention of claim 1 including a cap member which is removably attached to said case for covering the extending scissors within said case.

4. The invention of claim 1 including a detachable handle means connected to said case.

5. The invention of claim 1, including an L-shaped rearward portion on one of said snipping strips, an axis in said snipping strip forward of said L-shaped rearward portion, a push-button mounted on the L-shaped rearward portion, and opening means in said case so located to permit the push button to be exposed for hand actuation of 20 said scissors.
